UNITED STATES PATENT OFFICE.

WILLIS S. GIBBONS AND GEORGE E. BARTHOLOMEW, OF RUSSELL, NEW YORK.

WASHING-MACHINE.

SPECIFICATION forming part of Letters Patent No. 495,168, dated April 11, 1893.

Application filed March 30, 1892. Serial No. 427,090. (No model.)

To all whom it may concern:

Be it known that we, WILLIS S. GIBBONS and GEORGE E. BARTHOLOMEW, citizens of the United States, residing at Russell, in the 5 county of St. Lawrence and State of New York, have invented a new and useful Improvement in Washing-Machines, of which the following is a specification, reference being had to the accompanying drawings, forming part thereof.

Our invention relates to that class of washing machines in which a vertically reciprocating and intermittently revolving pounder is utilized in connection with a stationary tub 15 for holding the clothes, and it has for its object to improve the construction of such machines with a view to increasing their efficiency and ease and convenience of operation.

To this end our invention consists in the 20 washing machine constructed and operating as hereinafter fully described and particularly pointed out in the claims.

Referring to the drawings, in which like letters and numerals designate like parts in the 25 several views, Figure 1 is a plan view of our improved washing machine. Fig. 2 is a side elevation thereof, the tub and its false bottom being shown in vertical section. Fig. 3 is a view in perspective of the pounder. Fig. 4 is a 30 side elevation of the machine with the pounder raised to and held in its inoperative position. Fig. 5 is a detail view showing the adjustable guide-block for the pounder shaft. Fig. 6 is a plan view of the false bottom of the tub.

The letter *a* designates an ordinary wash-tub, which is shown as resting upon a bench *b* with its front, lower edge bearing against a cleat *b'* on said bench. In addition to its usual imperforate bottom said tub is provided 35 with a false bottom *b* having upon its under side a series of cleats *b* whereby it is sustained at a distance above the tub bottom corresponding to the thickness of said cleats, and which is provided with a series of radially 40 disposed slots *b* or other openings to permit a free circulation of water therethrough, as will be presently described.

The letter *c* designates the supporting standard, which is preferably made of wood, and 45 which extends from a point near the bottom of the tub, at the outer side of the latter, to a considerable distance above the top thereof,

as shown, and is provided with a suitably disposed shoulder *2* which bears upon the upper edge of the tub, and with a clamping member 55 *3*, which bears against the inner side of the tub and is adapted to be operated by a threaded bolt *4* and thumb-nut *5* to tightly clamp the standard upon the tub.

To facilitate holding the tub securely upon 60 the bench *b*, we prefer to provide the standard *c* with a cleat *6* near its lower end, through which passes a threaded bolt *7* having at its lower end a hook which is adapted to enter a staple *8* on the bench, and carrying at its upper end a thumb-nut *9*, by turning which the standard and the tub to which it is rigidly secured can be securely locked upon the bench, and as readily released therefrom.

The letter *d* designates the pounder-shaft, 70 which carries at its lower end the pounder *d'* and at its upper end the ratchet wheel *d*, and *e* designates the operating lever by which a vertical movement is imparted to said shaft, said lever being composed of two parallel 75 arms pivotally connected at their rear ends to the standard *c* and connected together at their front ends by the handle-bar *e'*. The arms of said lever are connected to standard *c* at a point but slightly above the plane of 80 the upper edge of the tub, thereby greatly conducing to the comfort and ease with which the lever can be operated as will be presently described. Between the arms of said lever is

85 pivotally supported a block *e*, which is preferably made of wood and has the trunnions or pivots at its ends inserted within suitable holes in said arms, said block being provided with a central opening through which passes the pounder-shaft *d* in such manner as to be 90 capable of a free revolving movement therein, while pins *10* entering one of a series of holes in said shaft, above and below said block, compel the shaft to partake of the vertical movements of the block, in a manner which 95 will be obvious from an inspection of Fig. 2 of the drawings. By providing the shaft with a series of holes to receive said pins *10* provision is made for adjusting the normal height of the pounder to correspond with the 100 quantity of clothes within the tub without affecting the normal position of the lever *e*.

A link-bar *f* is pivotally connected at its rear end to the standard *c*, near the upper end of

the latter, said bar being composed of two arms which are connected together by a cross-bar, f' , and between which is pivotally supported a block f^2 , similar to the block e^2 , and 5 through which the pounder-shaft passes in the same manner, the function of said link-bar being to maintain the pounder-shaft in an upright position, as is common in this class of machines.

10 As the angle at which the standard c stands will correspond with the angle of the side of the tub, which latter is far from uniform, and as it is important to a perfect operation of the pounder that the pounder-shaft shall 15 be maintained in a truly vertical position, we have provided means whereby this result can be secured regardless of the inclination of the side of the tub and standard c , such means consisting in devices whereby the block f^2 can 20 be adjusted toward and away from the pivotal center of the link-bar f . As herein shown, such adjustment is secured by causing the trunnions of said block to project through longitudinal slots 12 in the arms composing said 25 bar, and connecting to the outer end of each of said trunnions a slotted plate 13, through the slots in which plates extends a bolt 14, which constitutes the center of the cross-bar f' , and which carries at one end the thumb-nut 15. By loosening said thumb-nut the plates 13 and the block f^2 can be moved in either direction, and can be held in any desired position of adjustment by again tightening said nut, as will be fully apparent by 30 inspection of Fig. 5. Various other means for securing said adjustment can be employed within the spirit of our invention.

35 A pawl-carrier g is pivotally mounted upon the shaft d adjacent to ratchet-wheel d^2 , the spring-actuated pawl g' of which engages the teeth of said wheel, and a link-rod g^3 connected to the outer end of said carrier carries at its free end a hook, or other suitable device, whereby it is adapted to be detachably 40 connected to a bracket e^3 projecting upwardly from the lever e , said bracket being provided with one or more eyes 16 to receive said hook. When said link-rod is in its operative position, as shown in Fig. 2, each upward movement of lever e will impart a partial revolution 45 to the pounder-shaft through said rod, the pawl-carrier, and its pawl, and with each downward movement of said lever the pawl-carrier will be retracted to cause its pawl to 50 engage a new tooth of the ratchet-wheel. By detaching the end of said link-rod from the bracket e^3 the operative parts of the machine can be swung upwardly to the position shown 55 in Fig. 4, in which position the clothes can be readily placed in and removed from the tub, or a wringing machine can be attached to the tub and used in the ordinary manner. To 60 temporarily retain the parts in such elevated position we utilize a pin 17 suitably hung to 65 the frame, which is inserted through holes 18 in the bracket e^3 and one of the arms of link-bar f , said holes being brought into reg-

ister with each other when the parts are swung to their highest position.

The pounder d' is shown as being of a substantially rectangular shape, and having an open bottom, its interior being divided into sections by a vertical partition 19 extending from end to end thereof by a zig-zag line, as shown in Fig. 3. The object of thus dividing the interior of the pounder into sections is to increase its capacity for creating a suction upon the water within the tub, as it is lowered upon and raised from the clothes, and to thereby cause a circulation of the water through the clothes and through the openings in the false bottom b^2 , which action of the water results in a speedy and thorough cleansing of the clothes within the tub. The particular shape of the pounder is not material, however, so long as it retains this capacity for causing a circulation of water through the clothes. The operation of the washing machine thus constructed will be readily understood from the foregoing description.

The standard c being securely fastened to the tub by means of its clamping member 3, and the tub being secured to the bench by means of the bolt 7 and staple 8, the pounder-shaft is adjusted vertically within the blocks e^2 and f^2 to cause lever e to occupy a substantially horizontal position when the pounder rests upon the clothes within the tub. The operator then grasps the handle-bar e' and, by imparting an upward and downward swinging movement to lever e , causes the pounder and its shaft to move in a vertical plane, the former with each descent forcing the water through the clothes and through the openings in the false bottom b^2 , and causing an upward circulation of the water with each upward movement thereof by reason of the suction secured by its open bottom, the partial revolution imparted to the pounder-shaft during each upward movement thereof by the means described, causing the pounder to engage a new area of the clothes at each descent. Such continued operation quickly and thoroughly removes all dirt from the clothes after which, by securing the parts in the position shown in Fig. 4, a wringer can be secured to the tub and the clothes wrung out in the usual manner. By rendering the block f^2 adjustable within the link-bar f as described we are enabled to maintain the pounder-shaft in a truly vertical position regardless of the inclination of the side of the tub, and thereby secure a perfect suction action of the pounder under all circumstances.

The washing machine herein described is simple and inexpensive in construction and at the same time very strong and durable, and can be operated with perfect ease to thoroughly and quickly remove all dirt from the clothes.

Having thus fully described our invention, what we claim, and desire to secure by Letters Patent, is—

1. In a washing machine, the combination with an operating lever and a link-bar, pivotally connected at their rear ends to a common support and each carrying a pivotally supported bearing-block, of a pounder-shaft passing loosely through both of said blocks and carrying a pounder at its lower end, means substantially as described for causing said shaft to partake of the vertical movements of said operating lever, and means for adjusting the bearing-block on said link-bar toward and away from the pivotal center of said bar, substantially as and for the purpose described.

2. In a washing machine, a standard and means for detachably securing it to the side of a tub, a vertically disposed pounder-shaft carrying at or near its upper end a ratchet-wheel and at its lower end a pounder having an open bottom, an operating lever pivoted at its rear end to said standard and carrying a pivotally supported block which forms a bearing for said shaft, means for securing a vertical adjustment of the shaft within said block, a link-bar pivoted at its rear end to said standard above said operating lever and carrying a pivotally supported block which embraces said shaft, means for securing an adjustment of said block longitudinally of said bar, a pawl-carrier mounted upon said shaft and carrying a pawl which engages the teeth of the ratchet-wheel on the latter, and a link connection between said pawl-carrier

and an upwardly projecting portion of said operating lever, combined and operating substantially as described.

35

3. In a washing machine, the combination with the pounder-shaft *d* and operating lever *e* therefor, of the link-bar *f* composed of two parallel arms which are longitudinally slotted near their front end, block *f*² loosely embracing the pounder-shaft and provided with trunnions which project through the slots in said arms, plates 13 engaging the ends of said trunnions and slotted as described, and bolt 14 passing through the slots in said plates and carrying thumb-nut 15, substantially as and for the purpose described.

40

4. In a washing machine, the combination with standard *c*, of pounder-shaft *d* carrying ratchet-wheel *d*² at its upper end, lever *e* provided with the upwardly projecting bracket *e*³ and carrying the pivoted block *e*² which embraces said shaft, link-bar *f* carrying block *f*² also embracing said shaft, pawl-carrier *g* carrying pawl *g*' which engages said wheel *d*², 50 and link-rod *g*³ connected at one end to said pawl-carrier and having its opposite end adapted to detachably engage said bracket *e*³ on lever *e*, substantially as described.
